UNITED STATES PATENT OFFICE.

JOSEPH V. VAUGHN, OF DE LAND, FLORIDA.

COMB.

Application filed June 1, 1925, Serial No. 34,188. Renewed February 14, 1928.

This invention relates to improvements in toilet articles and has particular reference to combs.

An important object of the invention is to provide a comb designed especially for use to straighten hair.

A further object of the invention is the provision of a comb of this character which is so constructed as to be readily manipulated.

A still further object of the invention is the provision of a comb of the above character which is comparatively simple yet very durable in construction and efficient for the purpose intended.

Other objects and advantages of this invention will become apparent as the description progresses.

In the accompanying drawing forming a part of this specification and in which like numerals are employed to designate corresponding parts throughout the same:

Figure 1 is a side elevation of a comb constructed in accordance with my invention,

Figure 2 is a top plan view of a portion of the same, and

Figure 3 is a transverse sectional view taken on the line 3—3 of Figure 1.

In the drawing, wherein for the purpose of illustration is shown the preferred embodiment of my invention, the numeral 5 generally indicates the head of the comb which is preferably of cylindrical form and of any suitable material. Formed on one end of the head 5 and extending in alignment therewith is a handle shank 6 provided adjacent its outer end, with a shoulder 7, wire 8 being wound about the shank between the said shoulder and the inner end of the shank to permit convenient gripping of the handle thus formed.

Formed in a longitudinal series on one side of the body 5 and extending radially therefrom are relatively coarse teeth 9. A similar series of relatively fine teeth 10 is formed upon the opposite side of the head of the comb. With reference to Figure 3, it is seen that the teeth 9 and 10 lie in a common plane intersecting the axis of the head 5.

In use, the comb is primarily intended for straightening the hair so as to remove curls and kinks, being preferably used by

first engaging the coarse teeth 9 with the hair and then imparting slight rotary movement to the comb so that the hair will be trained over the side of the head 5 and be engaged by the fine teeth. In this manner the comb may be employed to straighten the hair and will obviate the use of pulling irons or similar apparatus which are extremely inconvenient and uncomfortable to the person. It will be evident by reference to Figures 2 and 3 of the drawings, and particularly the latter figure, that the head 5 of the comb is of a diameter considerably greater than the thickness of the teeth 9 and 10, so that, as the teeth of the two series occupy a common plane intersecting the axis of the head, the opposite sides of the head will project or extend a considerable distance at opposite sides of this plane and consequently when the comb is drawn through the hair in the manner illustrated in Figure 3, the hair will be straightened due to the passage of the convex surface of the head 5 of the comb thereover, the engagement of the hairs between the teeth of both series serving to sufficiently tension the hairs to bring about this desirable result.

It is to be understood that the form of my invention herewith shown and described is to be taken as the preferred example of the same and that various changes as to the shape, size and arrangement of parts may be resorted to without departing from the spirit of the invention, or the scope of the subjoined claim.

Having thus described my invention, I claim:

A comb for the purpose stated comprising a head of substantially cylindrical contour, a longitudinal series of relatively coarse teeth projecting radially from one side thereof, and a longitudinal series of relatively fine teeth projecting radially from the opposite side thereof, the teeth of the two series occupying a common plane, the opposite sides of the head between the series of teeth projecting beyond said plane to provide a curvilinear surface to be presented to hairs engaged and tensioned by the series of teeth.

In testimony whereof I affix my signature.

JOSEPH V. VAUGHN.
